[57] CLAIM

The ornamental design for a pair of eyeglasses, as shown and described.

DESCRIPTION

FIG. 1 is a front perspective view of a pair of eyeglasses embodying my new design;

FIG. 2 is a side elevational view thereof, the side opposite being a mirror image;

FIG. 3 is a top plan view thereof;

FIG. 4 is a front elevational view thereof;

FIG. 5 is a bottom plan view thereof;

FIG. 6 is a rear elevational view thereof;

FIG. 7 is a front perspective view of a second embodiment of a pair of eyeglasses embodying my new design;

FIG. 8 is a side elevational view thereof, the side opposite being a mirror image;

FIG. 9 is a top plan view thereof;

FIG. 10 is a front elevational view thereof;

FIG. 11 is a bottom plan view thereof; and,

FIG. 12 is a rear elevational view thereof.

FIG. 4

FIG. 5

FIG. 6

FIG. 10

FIG. 11
